PUMP PRIMING

Carl A. Bierlein, Cleveland, Ohio, assignor to
General Motors Corporation, Detroit, Mich., a
corporation of Delaware

Application June 19, 1951, Serial No. 232,433

7 Claims. (Cl. 123—41.09)

1

This invention relates to marine engine cooling systems having a plurality of cooling pumps and more particularly relates to priming means for one pump by another.

In internal combustion marine engines located well above the water line of a ship it is necessary to prime the sea water pump driven by the engine and having a sea water inlet pipe extending below the water line. In such systems an engine driven fresh water cooling pump is also provided and the water discharged therefrom is delivered to an exhauster to evacuate air and vapor from the sea water pump and inlet pipe to prime this pump. If evacuation is incomplete and there is not a sufficient head of water on the pump inlet the pump will lose its prime and repeated priming is necessary to obtain delivery therefrom.

The principal object of the present invention is to provide control means acting in response to a preselected delivery pressure of the pump being primed to discontinue the priming operation in order to provide prompt and continuous delivery pressure from the pump.

The combined engine cooling system embodying automatic pump priming control means for accomplishing this object together with other novel features thereof will become apparent by reference to the following description and drawings illustrating one modification of an engine cooling system and the automatic control means therein which is particularly adaptable for marine use.

Figure 1 of the drawings is a diagrammatic view of the complete engine cooling system showing the arrangement of the elements and connections therebetween.

Figure 2 is an enlarged longitudinal sectional view of a detail shown in Figure 1.

Figure 3 is an enlarged longitudinal sectional view of one of the valves shown in Figure 1.

Figure 4 is an enlarged longitudinal sectional view of certain other of the valve means shown in Figure 1.

As best seen in Figure 1 of the drawings, a water cooled internal combustion engine E, of the diesel marine type, is shown provided with fresh and sea water cooling pumps FP and SP driven by shafts 1 and 3 from the engine. The fresh water pump FP circulates fresh water through the engine cooling passages and fresh water passages in a heat exchanger HE through pipe connections 5, 7 and 9 in the direction of the arrows shown adjacent these connections for cooling the fresh water. The heat exchanger HE may also be provided with engine lubricating oil passages, not

2

shown, through which engine lubricating oil is circulated by an engine driven lubricating pump, not shown, for cooling the oil. An expansion tank ET also serving as a fresh water reservoir is located in the highest point of the engine cooling system and is shown provided with a filler cap 11 and an open vent pipe 13 on the upper end of this tank. A vapor vent pipe 15 is connected between a point in the expansion tank ET above the level of the water therein and the engine water outlet pipe 7 and a fresh water make up pipe 16 is connected between a point in the expansion tank, below the water level therein, to the inlet pipe 9 of the fresh water pump FP.

15 The sea water pump SP is provided with a sea water inlet pipe 17 extending downwardly to a point below the sea water level. The discharge opening of the sea water pump SP is connected by a sea water pump discharge pipe line 19 including a check valve 21 and a normally open, pressure actuated cut-off valve 23 to the inlet of the sea water passages in the heat exchanger HE and an overboard discharge pipe 25 is connected to the outlet of the sea water passages in the heat exchanger so that sea water is circulated therethrough in the directions of the arrows to cool the fresh water and engine lubricating oil in the fresh water and oil passages therein. The check valve 21 seats to prevent reverse flow through the pipe line 19.

20 In order to evacuate air and vapor from the water inlet pipe 17 and promptly prime the sea water pump SP, a suction pipe line 27 including a manual valve 29, a priming sea water cut-off valve 31 and a check valve 33, is connected between the sea water pump inlet pipe 17 and a suction port in an exhauster EX so that flow of air in the direction of the arrows may take place.

25 The check valve 33 in the suction line adjacent the exhauster EX seats to prevent flow of air in the reverse direction therefrom. The sea water priming cut-off valve 31 located in this line above the inlet of the sea water pump SP cuts off flow of sea water in this line at a level above the pump.

The exhauster EX, as best seen in Figure 2, is 30 of conventional type comprising a body 35 having an enlarged cavity 36 with a suction port 37 opening into one side wall thereof and a pressure inlet nozzle opening 39 and a coaxially disposed diverging outlet opening 41 in opposite ends of the cavity. The exhauster suction port 37 is connected to the suction pipe line 27, the exhauster outlet opening 41 is connected by a pipe fitting 43 to the upper portion of the expansion tank ET and the exhauster pressure inlet nozzle opening

39 is connected to the pressure discharge side of the fresh water pump FP, by means of a fresh water pump pressure pipe line 45, shown including a manual valve 47 and another normally open pressure actuated cut-off valve 23. It will be noted that the pressure pipe line 45 extends upwardly of the exhauster above the level of the fresh water therein to retain water in this line at all times.

The normally open pressure actuated cut-off valves 23 are best shown in Figure 4. Each of these valves comprises a body 49 having spaced water cavities 51 and 53 and a partition 55 between these cavities shown provided with a valve seat opening 57 extending laterally with respect thereto. The valve body 49 is provided with a cylindrical recess 58 in alignment with the valve seat opening 57. A valve stem 59 is slideable in a bore in the valve body coaxial with the recess 58 and valve seat opening 57 and a valve head 59' on the stem cooperates therewith. The end of the valve stem 59 shown within the recess 58 is secured to a diaphragm 61 clamped at the periphery thereof between the edge of this recess and a cylindrical pressure cap 63 by clamp bolts shown extending through openings in the cap and threaded to the valve body 49. A compression spring 65 is placed between the bottom of the recess 58 and the diaphragm 61 and a bleed port 67 is provided in the wall of this recess. The spring 65 normally retains the valve head 59' in spaced relation with the valve seat opening 57 and the cap 63 is provided with a pressure inlet opening 69 to allow pressure to act on the diaphragm and move it against the force of the spring 65 to cause seating of the valve head 59 in the seat opening 57 and cut off flow between the water cavities 51 and 53 in the valve body 49. The water cavities 51 and 53 in one of the valves 23 are connected in series in sea water pump discharge pipe line 19 and the pressure inlet opening 69 in the cap 63 of this valve is connected in a pressure pipe line 71 including a manual valve 73 to the pressure pipe line 45 connected between the outlet pipe 5 of the fresh water pump FP and the pressure inlet nozzle opening 39 of the exhauster EX. The water cavities 51 and 53 in the other valve 23 are connected in series in the pressure pipe line 45 between the fresh water pump FP and exhauster inlet nozzle opening 39 and the pressure opening 69 in the cap 63 of this valve is connected by a pressure pipe line 75 including a manual valve 77 to the sea water pump discharge pipe line 19.

The priming sea water cut-off valve 31, as best seen in Figure 3, is provided with a body 79 having a lower sea water cavity 81 and an upper suction cavity 83 and a partition 85 therebetween provided with a valve seat opening 87. A float valve 89 is located in the lower sea water cavity 81 and is seated in the valve seat opening 87 when the sea water enters this cavity through the suction pipe line 27 from the sea water inlet pipe 17 and reaches a level above that of the sea water pump inlet. The suction pipe line 27 is also connected to the upper portion of the upper suction cavity 83 of the valve body 79 and a gauge glass 91 is connected between the upper and lower portions of the suction cavity 83 to detect leakage of sea water past the float valve into the suction cavity.

Priming of the sea water pump SP starts upon starting and operation of the engine E and fresh water pump FP driven thereby. Fresh water under pressure is delivered by the fresh water

5 pump through the pressure pipe line 45 and exhauster EX to the expansion tank ET and through the pressure pipe line 71 leading from the pipe line 45 to the diaphragm in the valve 23 in the sea water pump discharge pipe line to cause closure of this valve. The suction developed by the exhauster EX is applied through the suction pipe line 27 to the sea water pump inlet pipe 17 to evacuate air and vapor therefrom and the sea water rises in this pipe and suction pipe line to a level in the lower cavity of the sea water priming cut-off valve 31 above the inlet of the engine driven sea water pump. The sea water pump then discharges sea water under pressure through the pressure pipe line 75 to the diaphragm of the valve 23 in the pressure pipe line 45 to exhauster EX, and the valve 59' of the diaphragm 61 thereupon cuts off the delivery of fresh water to the exhauster cavity 36 and also cuts off pressure through the pipe line 71 to the diaphragm of the valve 23 in the sea water pump discharge pipe line, causing this valve to be returned by the spring to the normal open position. Sea water may then be discharged through this valve, the heat interchanger and overboard discharge pipe to cool the engine cooling water and lubricating oil in the heat interchanger.

10 The above described cooling system provides prompt automatic priming of the engine driven sea water pump SP located above sea level and priming is continued until the sea water pump pressure builds up to a point necessary to discontinue priming thereof by the fresh water pump FP and exhauster EX and thus insures 15 continued discharge of sea water from the sea water pump. The combined fresh water reservoir and expansion tank ET provided with the vapor vent pipe 13 into which the water and vapor from the exhauster passes enables it to quickly evacuate the sea water pump of air and vapor and completely fill the inlet pipe 17 of the sea water pump SP. The sea water priming 20 cut-off valve 31 in the suction pipe line 27 limits the height of the sea water therein above the sea water pump and prevents sea water from entering the expansion tank and mixing with the fresh water therein and the check valve 33 in the suction pipe line 27 prevents air and vapor from being drawn from the expansion tank ET 25 into the sea water pump SP after it has been primed and is operating to insure maximum discharge therefrom.

25 I claim:

1. The combination of a driven, liquid pump having a normally open discharge valve and serving as a priming pump, a second driven, liquid pump, requiring priming, and having a normally open discharge valve, an exhauster having a fluid flow passageway and a suction passage communicating therewith, a suction pipe including a check valve interconnecting the exhauster suction passage and second pump to apply suction thereto, pressure operated means connected to the outlet of the priming pump discharge valve to close the second pump discharge valve to apply suction and prime said pump, and a second pressure operated means connected to the inlet side of said second pump discharge valve to close the priming pump discharge valve and permit the return of the discharge valve of the second pump to return to the normal, open position after build-up of liquid pressure in said second pump.

2. The combination of a driven, liquid pump having a spring opened discharge valve and

serving as a priming pump, a second driven liquid pump requiring priming, and having a spring opened discharge valve and check valve connected in series therewith, an exhauster having a fluid flow passageway connected to the discharge side of the priming pump discharge valve and a suction passage communicating with the exhauster fluid flow passageway, a suction connection including a check valve to connect the exhauster suction passage with the inlet side of the second pump to apply suction thereto, pressure operated means in communication with the inlet side of the exhauster fluid flow passage to close the discharge valve of the second pump to prevent fluid flow through said valve and check valve in series therewith and to start priming of said second pump, and other pressure responsive means communicating with the inlet side of the second pump discharge valve to close the discharge valve of the priming pump, and discontinue the priming of the second pump after a rise in liquid pressure therein.

3. The combination of a driven, liquid pump having a spring opened discharge valve and serving as a priming pump, a second driven liquid pump requiring priming, and having a spring opened discharge valve, an exhauster having a fluid flow passageway connected to the discharge side of the priming pump discharge valve and a suction passage communicating with the exhauster fluid flow passageway, a suction connection including a check valve and a float valve to connect the exhauster suction passage with the inlet side of the second pump to apply suction thereto, pressure operated means in communication with the inlet side of the exhauster fluid flow passage to close the discharge valve of the second pump to prevent fluid flow through said valve to start priming of said second pump, and other pressure responsive means communicating with the inlet side of the second pump discharge valve to close the discharge valve of the priming pump and discontinue the priming of the second pump upon a rise in liquid pressure therein.

4. The combination of an engine having a cooling water passage, a heat exchanger, a cooling water pump driven by the engine, pipe connections connecting the engine cooling water passage, the heat interchanger and cooling water pump in series, a combined water tank and vapor separator located above the engine and provided with an upper vapor vent, a pipe line interconnecting the upper portions of the engine cooling water passage and tank, a pipe line connecting the lower portion of the tank and inlet of the cooling water pump, an exhauster having a lower water outlet communicating with the upper portion of the tank, an upper water inlet nozzle and a suction port, a water pipe line including a spring opened valve connecting the exhauster inlet nozzle and outlet of the water cooling pump, a second water pump driven by the engine having a spring opened discharge valve and a downwardly extending water inlet pipe, a pipe line connecting the exhauster suction port to the inlet pipe of the second pump including a float valve located above the second pump and a check valve between the float valve and the suction port, pressure actuated means communicating with the inlet side of the exhauster nozzle to close the discharge valve of the second pump to apply suction to and thereby completely fill inlet pipe thereof with water, and a second pressure operated means communicating with the inlet side of the second pump discharge valve to close the

valve connected to the exhauster nozzle to discontinue operation of the exhauster.

5. In combination a marine engine having a fresh water cooling water passage, a fresh water pump and a sea water pump driven by the engine, said sea water pump having an inlet pipe extending downwardly therefrom below sea level, and a spring opened discharge valve, a heat interchanger having fresh and sea water passages, pipes connecting the fresh water pump in series with the fresh water passages in the engine and heat exchanger, pipes connecting the sea water pump discharge valve with the heat exchanger sea water passages, a tank located above the engine to serve as a combined fresh water tank and vapor separator and provided with an upper vapor vent, a fresh water supply pipe connected between the lower portion of the tank and inlet of the fresh water pump, an exhauster for the sea water pump having a fresh water passageway in communication with the upper portion of the tank and a suction passage communicating with the fresh water passageway, a pipe line interconnecting the exhauster fresh water passageway and outlet of the fresh water pump and including a spring opened valve, a suction pipe line connected at the upper end to the exhauster suction passage and connected at the lower end to the upper portion of the inlet pipe of the sea water pump, said suction pipe line including a float valve in the lower portion and a check valve in the upper portion to apply suction therethrough on the inlet pipe of the sea water pump, pressure operated means communicating with the outlet side of the valve connected to the outlet of the fresh water pump to close the sea water pump discharge valve and permit an increase in suction in the sea water pump to cause the sea water to rise to level above the sea water inlet pipe thereof and enter and close the float valve in the suction pipe line, the check valve in said suction pipe line closing to prevent down flow of fluid in said line, and a second pressure operated means communicating with the inlet side of the sea water pump discharge valve to close the valve in the fresh water line from the fresh water pump to the exhauster to cut off suction on the sea water inlet pipe when the discharge pressure of the sea water pump builds up.

6. In combination a marine engine having a fresh water cooling water passage, a fresh water pump and a sea water pump driven by the engine, said sea water pump having an inlet pipe extending downwardly therefrom below sea level, and a spring opened discharge valve, a heat interchanger having fresh and sea water passages, pipes connecting the fresh water pump in series with the fresh water passages in the engine and heat exchanger, pipes connecting the sea water pump in series with the heat exchanger sea water passages, a tank located above the engine to serve as a combined fresh water tank and vapor separator and provided with an upper vapor vent, a vapor vent pipe connecting the upper portion of the engine cooling passage with the upper portion of the tank, a fresh water supply pipe connected between the lower portion of the tank and inlet of the fresh water pump, an exhauster for the sea water pump located adjacent the tank and having a fresh water passageway in communication with the upper portion of the tank and a suction passage communicating with the fresh water passageway, a pipe line interconnecting the exhauster fresh water passageway and outlet of the fresh water pump and including a

spring opened valve, a suction pipe line connected at the upper end to the exhauster suction passage and connected at the lower end to the upper portion of the inlet pipe of the sea water pump, said suction pipe line including a float closed valve in the lower portion and a check valve in the upper portion to apply suction there-through on the inlet pipe of the sea water pump, pressure operated means communicating with outlet side of the valve connected to the outlet of the fresh water pump to close the sea water pump discharge valve and permit an increase in suction in the sea water pump to cause the sea water to rise to a level above the sea water inlet pipe thereof and enter and close the float valve in the suction pipe line, the check valve in said suction pipe line closing to prevent down flow of fluid in said line, and a second pressure means communicating with the inlet side of the sea water pump discharge valve to close the valve in the 20 fresh water line from the fresh water pump to the exhauster to cut off suction on the sea water inlet pipe when the discharge pressure of the sea water pump builds up.

5
10

7. The combination with a first liquid pump requiring priming, and having inlet and outlet lines, a liquid priming pump having inlet and outlet lines, evacuating means connected to the inlet line of the first pump and operable by pressure in the outlet line of the priming pump, a normally-open pressure-closable valve controlling the delivery of pressure from the outlet line of the priming pump to the evacuating means and closable in response to pressure at a point in the outlet line of the first pump, of a second, normally-open, pressure-closable valve controlling the outlet line of the first pump below said point and closable in response to pressure in the outlet line of the priming pump between said first named valve and the evacuating means.
